UNITED STATES PATENT OFFICE.

FRANK L. DODGSON, OF ROCHESTER, NEW YORK, ASSIGNOR TO GENERAL RAILWAY SIGNAL COMPANY, OF GATES, NEW YORK, A CORPORATION OF NEW YORK.

AUTOMATIC TRAIN-CONTROL SYSTEM.

1,416,622.

Specification of Letters Patent. Patented May 16, 1922.

Application filed February 23, 1917. Serial No. 150,499.

To all whom it may concern:

Be it known that I, FRANK L. DODGSON, a citizen of the United States, and resident of the city of Rochester, in the county of 5 Monroe and State of New York, have invented a new and useful Automatic Train- Control System, of which the following is a specification.

This invention relates to automatic train 10 control systems, and more particularly to systems of the type generally termed speed control systems.

One of the principal objects of this invention is to provide automatic means for governing railway trains so that these trains 15 may be permitted to approach close together with safety.

A further object of the invention is to provide a system for automatically controlling 20 the movement of a train not only in accordance with the speed at which that train is traveling and the space interval separating it from another train ahead, but also in accordance with the speed of the train ahead, 25 thereby facilitating the movement of trains by permitting them to travel with safety separated by a short space.

Other objects and advantages will appear 30 more fully hereinafter as the description of the invention progresses, and the novel features of invention will be pointed out in the claims.

In describing the invention in detail, reference is made to the accompanying drawings 35 in which are illustrated preferred embodiments of the invention, and in which like reference characters refer to like parts in the several views.

In the accompanying drawing, Fig. 1 is a 40 diagrammatic view of a railway track showing an arrangement of electrical circuits and devices associated therewith suitable for carrying out the invention;

Fig. 2 is a diagrammatic view showing 45 more in detail the parts of the timing apparatus;

Figs. 3^A, 3^B and 3^C are diagrammatic views 50 of the different electrical connections in certain circuits which are set up under different conditions;

Fig. 4 is a development of the contact

drum constituting a part of the timing apparatus;

And Fig. 5 is a diagrammatic view showing one form of a car-carried apparatus suitable for working in conjunction with the trackway circuits shown in Fig. 1.

Referring to Fig. 1, the numerals 1 and 2 designate the track rails of the usual railway track over which traffic normally moves from 60 left to right in the direction indicated by the arrow X.

The stretch of track is divided into short sections A, B, C, etc., by means of insulating joints 3 interposed at intervals in the track rail 1. The various devices and 65 electrical connections associated with the several track sections are the same, and for convenience these devices and electrical connections are given corresponding reference characters with distinctive exponents added. 70 Associated with each track section is a track battery 4 which is connected across the track rails 1 and 2 at one end of that section; and connected across the track rails 1 and 2 at the other end of the corresponding section 75 is a track relay 5 of any well known or suitable construction which is provided with contact fingers or armatures shown conventionally in Fig. 1.

Extending along the track is a continuous 80 ramp or contact rail R which is separated by suitable insulating joints 6 into sections RA, RB, etc., corresponding in length to the track sections. Associated with each track section is a suitable source of electrical energy 85 capable of delivering different voltages, this source being shown in Fig. 1 as a transformer T, the primaries of the several transformers being connected to the line wires 7 and 8 which are supplied with current from 90 a suitable alternating current generator 9. The various electrical connections between the secondaries of said transformers and the track rails and sections of the contact rails 95 will be pointed out more fully hereinafter in the description of the operation.

Associated with each of the track sections is a timing apparatus TA which is shown more in detail in Fig. 2. The timing apparatus for only one track section is shown in 100 Fig. 1, the others being indicated as dotted rectangles. As illustrated, this timing ap-

paratus comprises a shaft 10 supported in suitable bearings 11 and having fixed thereto a drum O of suitable insulating material. The drum O is provided with appropriate metallic contact strips, as 12, which are arranged to cooperate with a plurality of contact fingers, as 13, fastened to a suitable fixed insulating support 14. Connected to one end of the shaft 10 is a gear 15 which is driven by means of intermediate gears 16, 17 and 18 from a shaft 19 which is connected to a motor M having an armature 20 and a field 21. The motor M is constructed or controlled in some suitable manner so as to have a substantially constant speed when supplied with energy; and since various expedients capable of causing the motor to have a substantially constant speed are well known in the art, it is unnecessary to point out this feature of the invention in detail. Secured to the shaft 10 near its other end is a pulley 22 on which is wound a suitable cord or other flexible element 23, which is connected to a weight 24. The pulley, cord and weight are shown as a simplified form of a means suitable for exerting a constant tendency to turn the shaft 10 in a clockwise direction; but it is apparent that other devices for accomplishing the same purpose may be used. Secured to the shaft 10 is a ratchet wheel 25 which carries a fixed projecting arm 26 arranged to engage a fixed stop 27 so as to limit the rotation of the shaft 10 in a clockwise direction. A pivoted pawl 28 is arranged to cooperate with the teeth of the ratchet wheel 25, this pawl being shown as provided with a weighted end which constitutes the armature 29 of an electromagnet 30 and which tends to throw the pawl out of engagement with said teeth, the movement of the pawl under the influence of its weighted end being limited by a suitable stop 31. Associated with the parts of the timing apparatus TA hereinbefore described is a relay 32 of suitable construction, in this instance capable of responding to alternating current. The various electrical connections shown in Fig. 2 will not be described in detail since the operation of the timing apparatus, including the various electrical circuits established during this operation will be explained hereinafter.

Referring to Fig. 1 and more particularly to the section RA of the contact rail associated with the track section A, assume that no trains are present on the stretch of track illustrated. Also, for the moment disregard the action of the different timing apparatus and assume each is in its normal position, so that the connections established by the contact fingers and contact strips associated with its drum are as indicated in Fig. 1. Under these conditions a difference of potential is established between the contact rail section RA and the track rail 2 by a cir-

cuit which may be traced as follows: Commencing at the contact rail section RA, conductor 33¹, armature 34¹ of the track relay 5¹ in its upper position, conductor 35¹, conductor 41¹, armature 42² of the track relay 5² in its upper position, conductor 43², conductor 49³, armature 50³ of the track relay 5³ in its upper position, conductors 51³ and 52³, secondary of the transformer T³, and conductor 53³ back to the track rail 2. The voltage supplied to the contact rail section RA by the circuit just traced is equal to the entire voltage of the secondary of the transformer T³, and for convenience this voltage will hereinafter be referred to as high voltage.

Assuming that a train occupies the track section D, it will be readily apparent to those skilled in the art of railway signaling that the track relay 5³ will be shunted or de-energized and its armatures or contact fingers will assume their lower position. With the armature 50³ in its lower position the circuit hereinbefore traced is interrupted and a signal circuit including the conductor 55³ instead of the conductors 51³ and 52³ is established; and since the conductor 55³ is connected to the intermediate tap of the secondary of the transformer T³, the voltage supplied to the contact rail section RA is lower than formerly supplied when the track section D was not occupied, this lower voltage being conveniently termed medium voltage.

Assuming that the track section C is occupied, the armatures of the track relay 5² being in their lower position, the contact rail section RA is then connected by means of conductor 56² to another intermediate tap of the transformer, so that a still further reduced voltage is applied to said contact rail section, this voltage being conveniently termed low voltage.

Assuming that the track section B is occupied, it can be seen that no voltage will be supplied to the contact rail section by reason of the fact that the armature 34¹ of the track relay 5¹ will be in its lower position.

From the foregoing it can be seen that the voltage supplied to a contact rail section associated with a given track circuit section is dependent upon the number of unoccupied track circuit sections in advance thereof. In the particular arrangement shown in Fig. 1, the lengths of track circuit sections are made substantially equal to one-third of the braking distance for the particular portion of the railway track at which these track circuit sections are located. For example, the length of the track sections A, B and C is equal to the braking distance, so that with a train standing in the track section D, a following train entering the track section A will have sufficient distance to be brought to a stop by an application of its

brakes before reaching the entrance to the track section D. It is obvious, however, that the particular length of the track sections, and the number of voltages applied to the 5 contact rail sections may be varied as desired and as best adapted to the particular conditions under consideration.

The voltages applied to the contact rail section associated with the track section A 10 as hereinbefore explained are those existing in case the train, assumed to be occupying successively the track sections D, C and B, is standing still or traveling at a very low speed, and this does not apply, as will be explained hereinafter, to cases where the forward train is traveling at a comparatively high rate of speed; but prior to explaining the operation of the system when the forward train is traveling at a comparatively 20 high speed, it is considered expedient to describe the construction and operation of the car-carried apparatus shown in Fig. 5 so as to make it clear how the variation in the voltage applied to the contact rail sections 25 causes the proper control in the movement of the following train.

Referring to Fig. 5, the train is diagrammatically shown as comprising a pair of wheels 60 and an axle 61, and is illustrated 30 as carrying a suitable form of contact shoe S adapted to make electrical contact with the contact rail sections RA, RB, etc. For simplicity, instead of illustrating the track-way circuits as they are shown in Fig. 1, a 35 switch 62 is shown as arranged to connect the track rail 2 with taps of the secondary of a transformer T, corresponding to high, medium and low voltages hereinbefore referred to. The contact shoe S is connected 40 by conductor 63 to one terminal of a solenoid 64; and the other terminal of this solenoid 64 is connected by a conductor 65 to the frame or axle 61 of the vehicle, so that when the vehicle is traveling over the track an 45 electrical connection is established between said other terminal of the solenoid and the track rail 2. The core 66 of the solenoid 64 is connected by a link 67 to a lever 68 having a curved contact portion 69 at its end; and 50 a constant tendency to move the core 66 out of the solenoid 64 is exerted by a spring 70, one end of which is anchored in any suitable way, and the other end of which is connected to the link 67. The movement of the 55 lever 68 is limited by a suitable stop 71. Associated with the core 66 of the solenoid 64 is a time element device for limiting the rate of upward movement of said core, this device being shown conventionally as comprising a piston 57, having a flexible packing, movable in a cylinder 58 having a restricted inlet port 59 in its lower end.

The car-carried apparatus includes a suitable form of speed-responsive device G capable of indicating or establishing, by the

movement given to a part, the actual speed at which the vehicle is traveling at that instant. In the diagrammatic illustration of the invention shown in Fig. 5, this speed responsive device comprises weighted arms 70 72 pivotally connected to a collar 73 which is mounted on a squared portion of a shaft 74 so as to turn therewith but so as to be capable of sliding lengthwise thereon, the shaft 74 being driven from the axle 61 by 75 means of meshing beveled gears 75 and 76. Another collar 77 fixed to the shaft 74 is pivotally connected to links 78 which are also connected to intermediate points of the weighted arms 72. A compression coil 80 spring 79 is interposed between the collars 73 and 77. Located adjacent to the speed-responsive device G is a lever 80 having a curved contact piece 81 at one end and connected at its other end by means of a jaw 82 85 and pin with a collar 83 loose on the shaft 74. Arranged to contact with the curved contact pieces of the levers 68 and 80 are a plurality of contact springs 84 which are connected in pairs by a plurality of conductors 85.

The automatic train control apparatus is shown as capable of controlling the movement of the train by automatically causing an application of the brakes when necessary, although it is obvious that additional operations, such as shutting off the power may be also accomplished if desired. The particular embodiment of the invention illustrated in Fig. 5 is shown as applied to 100 the well known system of air brakes comprising a train pipe 86 which is connected to a suitable valve 87, it being understood by those skilled in the art that the opening of the valve 87 causes a venting of the train 105 pipe and results in an automatic application of the brakes. Arranged near the valve 87 is a brake controlling solenoid 88 having a vertically movable core 89, in which is fixed a pin 90 adapted to strike the arm 91 of the 110 valve 87 and cause an opening of said valve when the core 89 assumes its lowermost position. To the lower end of the core 89 is secured a piston 92 having a flexible packing, and the piston 92 fits in a cylinder 93 having a restricted exhaust orifice 94 in its lower end. It will be apparent that when the solenoid 88 is deenergized, its core 89 and the piston 92 will move downward due to their weight slowly in accordance with the rate at 120 which air escapes through the orifice 94, but if the solenoid 88 is reenergized, its core 89 may be quickly returned to its uppermost position. In general, the solenoid 88 and its associated parts constitutes a means for 125 operating the brake valve 87 after the lapse of a predetermined time following the deenergization of the said solenoid.

There is also preferably associated with the train control apparatus a warning signal 130

which is shown as an air operated whistle W. The operation of the whistle W is controlled by a solenoid 95 which operates a valve 96 contained in a suitable casing 97. 5 When the solenoid 95 is deenergized, the valve 96 is moved by its own weight to its lower position where communication is established from a suitable source of compressed air, such as the main reservoir 98 10 on the train through a pipe 99, valve casing 97, and passage 100 to the whistle W, thereby causing an immediate sounding of the whistle upon deenergization of the solenoid 95. The solenoid 95 controlling the whistle 15 W and the solenoid 88 controlling the brake valve 87 are included in series in a circuit, including a suitable source of current as a battery 101, conductors 102, 103, 104 and 105, which terminates at the levers 68 and 20 80. Between the levers 68 and 80 the circuit for said solenoids includes one or more of the conductors 85. The car apparatus 25 shown and described is merely typical of the kind of the car equipment which may be employed in accordance with my invention; and the detail construction and operation of this apparatus by itself in general forms no part of my present invention, being disclosed and claimed in other applications. 30 The operation of the car-carried apparatus shown in Fig. 5 is as follows: When the switch 62 is in the position shown, high voltage is applied to the contact rail section by a circuit traced as follows: commencing at the 35 contact rail section RA, conductor 105, secondary of transformer T, conductor 107, switch 62, and conductor 108 to the track rail 2. Thus sufficient current is supplied to the solenoid 64 so as to move its core 66 40 against the opposition of the spring 70 to the point where the lever 68 is in its uppermost position, as shown, where its curved contact portion 69 is in contact with each of the contact springs 84. With the lever 68 45 in this position, it can be seen that the lever 80 operated by the speed-responsive device G may be moved to its uppermost position (indicated by dotted lines) without interrupting the circuit through the solenoids 95 50 and 88 controlling the warning signal W and the brake valve 87, respectively. When the switch 62 is moved to an intermediate position, so as to apply a lower voltage to the contact rail section RA, less current flows 55 through the solenoid 64, so that the spring 70 moves the core 66 upward to an intermediate position, depending upon the voltage applied to the contact rail section. Assuming that this voltage is medium voltage, 60 the spring 70 will move the lever 68 to the point where it makes contact with all the contact springs 84 except the uppermost contact spring. Then, in order to prevent an interruption of the circuit through the solenoids 88 and 95, it is necessary for the curved

contact portion 81 of the lever 80 operated by the speed-responsive device G to move to an intermediate position in which it makes contact with the middle contact spring 84. In the same way, when low voltage is applied to the contact rail section the speed of the vehicle must be further reduced. 70

In general, the solenoid 64, together with its associated parts, constitutes a means for establishing a permissive speed for the vehicle in accordance with the voltage applied to the contact rail sections. If the actual speed of the vehicle, which is indicated by the speed responsive device G, exceeds the permissive speed, the circuit for energizing 75 the solenoids 88 and 95 is interrupted, and the warning signal W is immediately sounded, and the core 89 of the brake controlling solenoid 88 commences to move downward. It is contemplated that the engineer 80 or motorman of the train, upon the sounding of the warning signal W, will immediately shut off the power and apply the brakes; and the apparatus is preferably so arranged that when the engineer or motorman obeys the 85 warning signal in this way, he will be able to cause sufficient reduction in the speed of the vehicle as to re-establish the circuit through the brake controlling solenoid 88 prior to the lapse of time for which the 90 dash-pot device is adjusted. In other words, the system is preferably so constructed that the engineer or motorman, by promptly obeying the warning signal W, may avoid an automatic application of the brakes. In 95 this connection suitable recording or registering devices may be used in conjunction with the brake controlling solenoid 88 so as to enable a record to be made whenever an automatic operation of the system occurs. 100 Such recording devices are well known in the art and need not be described in detail.

Referring now to Fig. 1, assume that a train equipped with the apparatus shown in Fig. 5, enters the track section A when another train is standing in the track section D. It can be seen that the following train is compelled automatically to reduce its speed as it moves through the successive track sections B, C and D toward the forward train, by reason of the fact that the successive contact rail sections RA, RB, RC are supplied with successively lower voltages, as previously explained; and the successive reductions in speed compelled by the 115 automatic apparatus are selected with a view of bringing the following train to a stop or to a predetermined low speed by the time it reaches the end of the block C. 120

It may well happen that when a train approaches so close to a train ahead as to make it desirable to retard the following train, the forward train will be traveling at a comparatively high rate of speed so that, even if it were to immediately apply its brakes it 125 130

would travel considerable distance. Thus, if it is taken into consideration that the forward train is traveling at a comparatively high speed and cannot under the worst conditions be brought to a stop for a considerable distance, it can be seen that the following train may approach closer to the forward train with proper safety than would be the case if the forward train were standing still. In other words, if the relative braking distances of two trains is made the determining factor of whether or not an automatic governing of the following train should occur, the physical space interval between the two trains may be materially reduced; and one of the important features of this invention is its capability of making the speed of the forward train one of the determining factors in the automatic control of the following train. In the particular embodiment of the invention illustrated the speed of the forward train is determined by ascertaining the time taken by said train to travel a predetermined distance. In accomplishing this purpose it is desired to use as much as possible the parts of the trackway circuits which are necessarily used in order to afford the proper control of the train when the forward train is standing still, and according to the embodiment of the invention illustrated, the time is measured from the time the rear end of a train leaves a given track section until it leaves the next track section in advance.

Referring to Fig. 2, assume that a train, traveling from left to right in the normal direction of traffic, enters the track section B, progresses into the track section C and finally entirely leaves the track section B. At the instant when the rear end of the train leaves the track section B the track relay 5¹ is reenergized and its armature 109 raised so that a circuit for energizing the relay 32 is established as follows: commencing at one terminal of the secondary of transformer t, conductors 111, 112 and 113, armature 109 of the track relay 5¹ in its upper position, conductor 114, armature 110 of the track relay 5² in its lower position, conductors 115 and 116, contact finger 117, contact strip 118, contact finger 119, conductors 120 and 121, relay 32 and conductors 122, 123 and 124 back to the other terminal of the secondary of said transformer.

Referring to Fig. 4, it can be seen that the contact strip 118 is of such a length and so arranged that after a slight movement of the drum O the electrical connection between the contact fingers 117 and 119 is broken, the purpose of this arrangement being pointed out hereinafter. When the relay 32 is energized and its armature 126 raised, a shunt is established around the contact fingers 117 and 119 comprising conductor 125, armature 126 of said relay in its upper position and conductor 127, so that after the relay 32 is once energized, and although its energizing circuit is immediately interrupted by the movement of the drum, the relay 32 is maintained energized by its maintaining or stick circuit until the armature 110 of the track relay 5² resumes its upper position due to the movement of the train entirely out of the track section C. The raising of the armature 128 of the relay 32 closes a circuit for supplying energy to the motor M, said circuit being traced as follows: commencing at one terminal of the secondary of the transformer t, conductors 111, 112 and 129, contact finger 130, contact strip 12, contact finger 13, conductor 131, armature 20 of the motor M, field 21 of said motor, conductor 132, armature 128 of the relay 32 in its upper position and conductors 133 and 124 back to the secondary of said transformer. The motor M gradually turns the shaft 10 in a counterclockwise direction against the opposition of the weight 24 at a rate corresponding to time. As the train progresses and its head end enters the track section D, the armature 136 of the track relay 5³ assumes its lower position and energizes the electromagnet 30 by a circuit traced as follows: commencing at one terminal of the transformer t, conductors 111 and 134, electromagnet 30, conductor 135, armature 136 of the track relay 5³ in its lower position, and conductors 137, 123 and 124 back to the other terminal of the secondary of said transformer. The energizing of the electromagnet 30 moves the pawl 28 into position to engage with the teeth of the ratchet wheel 25, but does not interfere with further movement of the shaft 10 and the contact drum O by the motor M. As the train progresses and entirely leaves the track section C, the track relay 5² is again energized and its armature 110 is raised so as to interrupt the stick circuit through the relay 32, thereby stopping the motor M. The contact drum O will be held in the position into which it has been moved by the action of the pawl 28, so long as the train remains in the track section D. When the train leaves track section D, the electromagnet 30 becomes de-energized, the pawl 28 disengages from the teeth of the ratchet wheel 25, and the shaft 10 and contact drum O are returned to their normal or initial position by the weight 24. From the foregoing, it can be seen that the position assumed by the shaft 10 and contact drum O becomes a measure or indication of the speed of the train while passing over the corresponding track section.

Referring particularly to the track section C, suppose that the speed of the train, determined by the time taken it to pass over the track section C is such that the train cannot even by an immediate application of

its brakes be brought to a stop until its rear end has traveled beyond the track section D. With such conditions existing it can be seen that it is permissible to increase the voltage applied to the contact rail sections RA and RB associated with the track sections A and B in the rear thereof to the voltage which would ordinarily be applied to these contact rail sections if the forward train were standing in the track section E, that is, just the same as if the train had already passed over the track section D. Likewise, if the speed of the train, indicated by the time taken it to travel over the track section C, is so great that said train cannot be brought to a stop by its brakes until after its rear end has passed beyond the track section E, it can be seen that the voltage applied to the contact rail sections RA and RB associated with the track sections A and B may be still further increased with safety; that is, if the forward train cannot be stopped until it has passed over the track sections D and E, it is permissible to permit the following train to run at the same speed as if the track sections D and E were as a matter of fact not occupied. This change in the voltage is produced by changing the connections between the contact rail sections and the respective sources of current to which they would ordinarily be connected in accordance with the position of the armatures of the track relays, and this change in connection is produced by the movement of the contact drum O. Referring to Figs. 3 and 4, Fig. 3^A illustrates the connection to be established under normal conditions when the forward train is standing still, Fig. 3^B illustrates the connections which should be established when the forward train is traveling at a high speed, that is, when it consumes a short time in traveling over the length of a track section, and Fig. 3^C illustrates the connection which should be made when the forward train is traveling at medium speed. Fig. 4 illustrates the development of the contact drum O and the inter-connections between the several contact strips thereon necessary to obtain the connections in the parts of Fig. 3, the contact drum being rotated in a direction such that in its developed form shown in Fig. 4 it moves from right to left under the contact springs.

Referring to Fig. 1, assume that the forward train travels over the track section C in such a short time that it is assured that it could not come to a stop until after passing over the track sections D and E. The timing apparatus will be operated as hereinbefore described but the contact drum O will only be moved a very short distance during this short time, that is, to the first position shown in Fig. 4, in which the connections shown in Fig. 3^B are established. With these connections established, high voltage is applied to contact rail section RB associated with the track section B and also high voltage is applied to contact rail section RA. The circuit for the contact rail section RA of the track section A may be traced as follows: 70 commencing at the contact rail section RA, conductor 33¹, armature 34¹ of the track relay 5¹ in its upper position, conductor 35¹, conductor 41¹, armature 42² of the track relay 5² in its upper position, conductor 43², 75 then referring to Fig. 4, remembering that the contact drum O is now in its first position, contact finger 44, contact strip 144, connector 143, contact strip 142, contact finger 140 conductors 141³ and 52³, secondary of the 80 transformer T³ and conductor 53³ to the track rail 2. The circuit for the contact rail section of the track circuit section B may be traced as follows: commencing at the contact rail section RB, conductor 33², armature 34² 85 of the track relay 5² in its upper position, conductor 35², then referring to Fig. 4 and remembering that the contact drum O is in the first position, contact finger 36, contact strip 144, connector 143, contact strip 142, 90 contact finger 140, conductors 141³ and 52³, secondary of the transformer T³ and conductor 53³ to the track rail 2. Since there is high voltage applied to the contact rail sections RA and RB, the following train will 95 be permitted to proceed at high speed through the track sections A and B just as if the three track sections C, D and E ahead were not occupied; whereas without the timing apparatus, the following train would 100 have to reduce its speed in traveling through the track sections A and B so long as the forward train remained in the track section D.

In a similar way, if the forward train 105 is traveling at such a speed that it must necessarily pass beyond the track section D before it can be brought to a stop, the contact drum O is moved to a further or second position in which the connections are established as shown in Fig. 3^C. With these connections established, high voltage is applied to the contact rail section RA associated with the track section A and medium voltage is applied to the contact rail section 110 RB associated with the track section B. The circuits for the contact rail sections RA and RB may be easily traced from analogy to those already traced, it being remembered that the contact drum O is now in its second position (see Fig. 4) so that a connection is established between conductors 35 and 49 by contact strips 145 and 147 and connector 146, while the connection between conductor 43 and 49 is continued by the extended contact strips 144 and 142. 115

It should be noted that the contact drum O is being rotated to its new position only while the train occupies the corresponding track section, as the track section C, and 120

125

130

that during this time the presence of the train on this track section disconnects the conductors leading to the drum, as the conductors 35² and 43², by reason of the fact 5 that the armatures, as 34² and 42², of its track are in the lower position. In this way, the connections established by the position 10 to which the drum O is moved are not capable of being effective until it has been determined to what position the drum should be 15 moved according to the speed of the forward train. It should also be noted that after the drum O has once been moved to a given position and is held in that position by the action of the pawl 28 and electromagnet 30, it cannot be moved to any other position 20 until it has again resumed its initial or normal position. This is due to the operation of the contact fingers 117 and 119 which interrupt the circuit for initially energizing the relay 32 as soon as the drum O has commenced its movement. When the time taken 25 for the train to travel over the particular track section has elapsed, the stick circuit for the relay 32 is broken at the armature 110 of the track relay, and hence before it is possible to again energize the relay 32 and supply power to the motor M, it is necessary 30 for the contact drum O to return to its initial position and again establish an electrical connection between the contact fingers 117 and 119 so as to permit the relay 32 to be again initially energized.

In case the train in the track section C is standing still, or is traveling at such a low speed that it might be brought to a stop by an application of its brakes before entirely leaving said track section C, the time during 35 which the timing apparatus is being operated is so great that the contact drum O is moved substantially a full revolution to the third position shown in Fig. 4 in which the electrical connections established between the respective contact fingers 36, 44, 40 and 45 48 are the same as are established in the normal or initial position of the drum. In other words, when the forward train is standing still or is traveling at a low speed, the voltages applied to the contact rail sections 50 of the track sections in the rear are the same as if the timing apparatus were omitted. In order to avoid damage in case a train should remain in a track section, as a track section C, for a considerable time, 55 arrangements are made to cut off the supply of current to the motor after the contact drum O has been rotated through approximately one revolution, this result being accomplished by making the contact strip 12 60 of the proper length as shown in Fig. 4.

The timing apparatus, as explained hereinbefore, is associated with each track circuit section and operates to increase the voltage applied to the contact rail sections 65 in the rear according to the time taken by

the rear end of a train to travel through the track section associated with that particular timing apparatus, that is, the timing apparatus associated with each track section constitutes a means for varying the control 70 applied to a following train according to the speed of the forward train at the particular place where the track section in question is located, so that for all parts of the stretch of railway equipped with the automatic 75 train control system embodying this invention, trains are permitted to run at a spacing or distance apart depending substantially upon their relative braking distances. Consequently, the system embodying this invention 80 enables trains to be spaced closer together with proper safety and in this way enables a greater facility of movement of the trains. The system herein shown and described including the timing apparatus 85 may be applied to the entire length of a railway or any particular sections or portions thereof, as may be desired. It is also contemplated that special conditions may make it desirable to use the system with the 90 timing apparatus for some parts or sections of the railway while for other parts of the railway it will not be necessary to use the timing apparatus in the system.

From the foregoing it can be seen that in 95 accordance with this invention provisions are made such that when a train is standing still on any portion of the railway track, its presence is detected, and a manifestation of its presence appears as varying voltages applied to the several contact rails throughout 100 a zone in the rear of said train, the extent or length of this zone being determined by the distance required for a following train to be brought to a stop or to a predetermined 105 low speed by an application of its brakes. Also, if the forward train is moving, its rate of movement or speed determines the length of the zone. If the forward train is moving at a comparatively high speed, the zone is 110 made considerably shorter, whereas if the forward train is moving at a lower speed the zone is not shortened as much. Thus, within the limits due to the particular character of the embodiment of the invention illustrated, 115 the speed of the following train is made dependent upon the speed of the forward train and the distance between the following train and the forward train. The contact rails and contact shoes, which are made a part of 120 the particular embodiment of the invention illustrated and hereinbefore described, have been selected as simple examples of a suitable form of a means adapted to establish communication between a moving train and 125 impulse devices along the track; but it is to be clearly understood that I contemplate as falling within the scope of my invention other forms of communicating devices, the different controlling conditions of said com- 130

municating devices being produced by variations in the voltage applied thereto or by other expedients in accordance with the particular character of the communicating means.

Various modifications and applications of the system embodying this invention, other than those illustrated and described and which utilize the important and desirable features of this invention, will be readily apparent to those skilled in the art of railway signaling after acquiring a thorough knowledge of the invention. Among such changes and modifications, the speed control apparatus responding to the varying controlling conditions, namely the varying voltages applied to the several contact rail sections, may take other forms than the specific type of apparatus illustrated and described; and in the same way other arrangements of trackway circuits, involving the same principles of operation, might be used. The particular embodiment of the invention selected to illustrate the principles of operation and important features of the invention, has been illustrated and described with special reference to double track railways in which trains normally run in one direction on each track; but I wish it to be clearly understood that I contemplate the application of my invention to single track railways and to other special cases. Consequently, although I have particularly described the construction of one physical embodiment of my invention, and explained the operation and principle thereof; nevertheless, I desire to have it understood that the form selected is merely illustrative, but does not exhaust the possible physical embodiments of the idea of means underlying my invention.

What I claim as new and desire to secure by Letters Patent of the United States, is:

1. In an automatic train control system, in combination: a railway track; trackway means responsive to the presence of a train on said track for creating a zone of variable influence extending in the rear of said train for a distance corresponding approximately with braking distance for the trains; means controlled by the speed of said train for varying the length of said zone; and means on the following train responsive to the influence of said zone for limiting its speed in accordance with its location in said zone.

2. In an automatic train control system, in combination: a railway track; communicating means along the track for communicating to trains thereon; means responsive to the presence of a train on said track and its speed for establishing varying controlling conditions of said means at different points in the rear of said train throughout a zone of limited extent; the controlling conditions of said communicating means at the

different points in said zone being dependent upon the distance between that point and the point where said train may be brought to a stop by the action of its brakes; and means on a following train responsive to the varying controlling condition of said communicating means for limiting the speed of said following train.

3. In an automatic train control system, in combination: a railway track; impulse devices along said track adapted to have different controlling conditions; trackway means responsive to the presence of a train on said track and its speed for establishing different controlling conditions of the impulse devices in the rear thereof throughout a zone of limited extent which has its length dependent upon the speed of said train; and means on a following train controlled by said impulse devices for imposing a limitation upon the speed of said following train in accordance with the controlling condition of said impulse devices.

4. In an automatic train control system for railroads having tracks divided into track sections each provided with a track relay, speed control apparatus on a vehicle comprising a permissive speed element movable to different positions in accordance with the intensity of electrical energy supplied thereto, an actual speed device assuming different positions in accordance with the actual speed of the vehicle, brake setting means controlled jointly by said permissive speed element and said actual speed device, and trackway means controlled by said track circuits and adapted to supply electrical energy to the vehicle varying in intensity in accordance with the location and speed of a train ahead.

5. In an automatic train control system, in combination: a railway track divided into track sections; an impulse device associated with each track section and adapted to have varying controlling conditions; means responsive to the presence of a train on each track section for giving varying controlling conditions to the impulse devices associated with a predetermined number of track sections in the rear; means dependent on the speed of said train through said track section for modifying the controlling conditions of said impulse devices in the rear; and means on a following train responsive to the varying controlling conditions of said impulse devices for regulating the speed of said following train.

6. In an automatic train control system, in combination: a railway track divided into track sections each having a track relay; a contact rail associated with each track section; means controlled by the track relay of each track section for applying different voltages to the contact rails of a predetermined number of said track sections in the rear; means

- controlled by the speed of a train traveling through each track section for changing the voltages applied to the contact rails of the track sections in the rear in accordance with 5 the speed of said train; and means on a following train responsive to the variations in the voltage applied to said contact rails for limiting the speed of said following train.
- 10 7. In an automatic train control system, in combination: a railway track divided into track sections; impulse devices along the track adapted to have different controlling conditions; means responsive to the presence 15 of a train on a track section for giving varying controlling conditions to the impulse devices for a limited distance in the rear thereof; timing apparatus associated with each track section for determining the time 20 taken by the rear end of a train to pass through the track section; means controlled by said timing apparatus for changing the controlling conditions of the impulse devices in the rear of the corresponding track 25 section in accordance with the time of operation of said timing apparatus; and means on a following train for limiting its speed in accordance with the controlling conditions of said impulse devices.
- 30 8. In an automatic train control system, a railroad track divided into track circuit sections, a plurality of said track sections constituting braking distance for the vehicles traveling over the track, impulse transmitting means extending throughout the length of each track section and effective to transmit controlling influences to a passing vehicle in accordance with the voltage applied to said impulse transmitting means, 35 means responsive to the presence of a vehicle on said track sections and its speed through such track section for supplying different voltages to the impulse transmitting means of a number of track sections in the 40 rear thereof, and means on a following vehicle for imposing restrictions on its speed in accordance with the varying controlling influences communicated to it in the successive track sections, whereby the speed of the 45 following vehicle will be restricted in accordance with the distance between it and the vehicle ahead and also the speed of the vehicle ahead.
- 50 9. In an automatic train control system, a railroad track divided into track circuit sections, impulse transmitting means associated with each track section and capable of assuming different controlling conditions, time controlled apparatus associated with 55 each track section and governed by the track circuits of that track section and the track section next in the rear, said apparatus acting to vary the controlling conditions of the impulse transmitting means of a number of 60 track sections to a limited distance in the rear in accordance with the time taken by a vehicle to travel through the track section corresponding to said apparatus, and speed control apparatus on the following vehicle responsive to the varying controlling conditions of said impulse transmitting means. 70
10. In an automatic train control system, a railroad track divided into track circuit sections, a plurality of said track circuit sections constituting braking distance for the 75 vehicles traveling over the track, impulse transmitting means for each track section, means associated with each track section for placing its impulse transmitting means in a predetermined condition in accordance with 80 the number of unoccupied track sections of said plurality in advance thereof, and means responsive to the speed of a vehicle in any one of said plurality of track sections for modifying the controlling condition of said 85 impulse transmitting means associated with the track sections in the rear, whereby the controlling condition of the impulse transmitting means of each track section is automatically dependent upon the number of unoccupied track sections in advance thereof and also upon the speed of the vehicle in the 90 first occupied track section.
11. In an automatic speed control system adapted to regulate the speed of vehicles in 95 accordance with the distance to the next vehicle ahead and also the speed of said vehicle ahead, a track divided into track circuit sections, a plurality of which constitute braking distances for the vehicles, means 100 including impulse transmitting devices for imposing varying speed restrictions on a following vehicle in each track section in accordance with the number of unoccupied track sections of said plurality in advance thereof, and means including time controlled apparatus adapted to determine the speed of the vehicle in any one of said advance track sections for modifying the action of 105 said first mentioned means to permit higher 110 speeds for the following vehicle.
12. In an automatic train control system, the combination with a vehicle, of a permissive speed device on the vehicle biased to assume its lowest speed condition, means 115 partly on the vehicle and partly along the track for causing said permissive speed device to assume higher speed conditions in opposition to its bias, and means compelling 120 said permissive speed device to change slowly to its lowest speed condition in response to its bias but permitting a quick change to higher speed conditions.
13. In an automatic train control system, the combination with a vehicle, of a permissive speed device on the vehicle biased to assume its lowest speed position, electrically operable means for causing said permissive speed device to assume higher speed positions in opposition to its bias, time con- 125 130

trolled means for regulating the change of said permissive speed device to its lowest speed position, a speed responsive device establishing the actual speed of the vehicle, 5 and a safety appliance for excessive speed operated when the actual speed of the vehicle exceeds the permissive speed prescribed by said permissive speed device.

14. In an automatic train control system, 10 a track divided into track circuit sections, time controlled apparatus associated with each track section and adapted to determine the speed of vehicles traveling through that track section, said time controlled apparatus 15 comprising a movable element, a motor for moving said element in accordance with time, and control means governed by the track circuits of the corresponding track section and the track section next in the rear 20 and adapted to cause said motor to operate from the time a vehicle leaves the rear track section until it leaves the advance track section.

15. In an automatic train control system, 25 a track divided into track circuit sections, time controlled apparatus associated with each track section and adapted to determine the speed of vehicles through that track section, said apparatus comprising a movable element biased to one position, a motor for moving said element from its biased position in accordance with time, control means governed by the track circuits of the corresponding track section and the track section 30 next in the rear for causing said motor to operate during the time elapsing between the successive re-energization of said track circuits, and means controlled by the track circuit of the track section next in advance 35 of the track section corresponding to said apparatus for maintaining said movable element in its moved position against the opposition of its bias so long as said advanced track section is occupied.

45 16. In an automatic train control system, speed control apparatus on a vehicle including a permissive speed device biased to its lowest speed condition, means partly on the vehicle and partly along the track for causing 50 said device to assume higher speed conditions in accordance with the location and speed of a train ahead, and a brake setting appliance acting to apply the brakes automatically when the actual speed of the vehicle exceeds that prescribed by the existing 55 condition of said permissive speed device.

17. A speed control system for railroads divided into short track sections each having a track circuit, comprising impulse devices along the track adapted to assume different controlling conditions corresponding to the safe speed limit for a following train, 60 means for governing the controlling condition of said impulse devices by said track circuits, and means responsive to the time

required for the rear end of a train to pass over a track circuit for independently controlling said impulse devices, whereby the controlling condition of said devices is dependent upon the distance to the next train 70 ahead and the speed of that train.

18. An automatic speed control system for railroads divided into track sections each provided with a track circuit, comprising a trackway impulse device associated with 75 each track section, means responsive to the presence of a train on a given track section for causing the impulse devices of a number of track sections in the rear thereof to assume permissively varying controlling conditions, and means responsive to the time taken by the rear end of a train in traveling through said given section for independently controlling said impulse devices in the 80 rear.

19. In an automatic train control system for railroads divided into track sections, impulse devices associated with said track sections, and means for governing groups of said devices, said means comprising time responsive means and a governing circuit therefor which includes front and back contacts of the track relays of two adjacent track sections, whereby said time responsive means is operated while the rear end of a 95 train is passing through the corresponding track section.

20. In an automatic train control system for railroads divided into track sections each provided with a track relay, the combination with speed controlled apparatus on a vehicle adapted to enforce varying restrictions upon the speed thereof, of trackway means controlled by the track relays for creating a zone of variable influence in the 100 rear of a train occupying a given track section, which zone of influence varies in extent in accordance with the time taken by that train to pass through a track section, said zone of influence being adapted to control 105 the speed control apparatus on a following vehicle.

21. In an automatic train control system, the combination with car apparatus comprising permissive speed means responsive 115 to electric energy of varying characteristics, and brake control means operated when the car exceeds a speed corresponding to that prescribed by the existing condition of said permissive speed means, of trackway means 120 including a continuous conductor and sources of electrical energy of different characteristics for influencing said permissive speed means to a variable degree dependent upon the distance between the car and the next train ahead and also the speed of said train ahead.

22. An automatic system for regulating the speed of railroad trains comprising brake governing apparatus on the train adapted to 130

- cause an automatic brake application when the train exceeds predetermined variable speed limits, said apparatus having a tendency to assume an active condition and stop the train, and automatic means for continuously influencing said apparatus and put it in a speed limiting condition dependent upon the distance to the next train ahead and the speed of that train ahead, said automatic means comprising a time element device automatically controlled by said train ahead. 5
23. In an automatic speed control system for railroads, a changeable permissive speed means on a car biased toward its lowest speed condition, cooperating car carried means and trackway means for continuously influencing the permissive speed means to maintain it in a speed limiting condition corresponding to the extent of unoccupied 10 track ahead of the car, and trackway means controlled by the speed of a train traveling thereby for modifying such influence upon the permissive speed means on a following car, whereby the permissive speed means on 15 a car is regulated in accordance with the distance between it and the next car ahead and also the speed of said car ahead. 20
24. In an automatic train control system comprising a continuous conductor along the track divided into sections, a plurality of 25 which constitutes braking distance for the trains traveling over the track, trackway means including sources of current of different voltage for energizing each section of said conductor with a voltage dependent upon the distance between that section and the next train ahead and also the speed of 30 said train ahead. 35
25. A train control system comprising means including track devices for imposing predetermined speed restrictions on passing vehicles at a plurality of control points in the braking distance thereof, and trackway means responding to the speed of trains for modifying the action of said track devices braking distance in the rear of such train and thereby permit higher speeds for a following vehicle. 40
26. In an automatic train control system comprising means including track devices for automatically determining the speed limit for passing vehicles in accordance with the extent of unoccupied track in advance thereof, and trackway means influenced to a variable degree by the speed of a train for modifying the influence of the track devices throughout braking distance in the rear of that train and thereby establishing higher speed limits for a following vehicle dependent upon the speed of said train ahead. 45 50 55
